GRID PASTING MACHINE

Arthur D. Lund, Minneapolis, Minn.

Application September 21, 1935, Serial No. 41,584

34 Claims. (Cl. 226—39)

This invention relates to machines for filling or pasting storage battery grid plates, and the main object is to provide improved mechanism not only for more accurately and efficiently applying the electro-chemical active paste material, but also for conveying, guiding, and controlling the grid plate movement to and through the paste applying zone. More particularly the invention presents a number of improvements 5 over the Grid pasting machine as disclosed and claimed in my earlier copending application Ser. No. 726,744, filed May 21st, 1934, and attention is directed to that application for a more detailed and complete description particularly of 10 mechanisms and features which are here either omitted or shown in less detail to avoid duplication or repetition of disclosure. The present application concerns itself primarily with structural features and combinations of devices which 15 distinguish from those of the earlier application and will now be described in detail, reference being made to the accompanying drawings wherein like characters designate like parts in the various views, and in which—

Fig. 1 is a side elevation of the machine, the left or operator's end of the machine as shown in this view being considered, for purpose of convenience, in description, the front end.

Fig. 2 is a side elevation of the machine opposite to that shown in Fig. 1.

Fig. 2a is a detail plan view of the rear or left end of the machine as shown in Fig. 2.

Fig. 3 is an enlarged detail elevation of the grid feeding unit, as shown at the left of Fig. 1, this unit being detached from remaining portions of the machine except for the driving shaft and pinion at the right end, which shaft and pinion are shown as on the section line 3—3 in Fig. 4.

Fig. 4 is an enlarged plan view of the front end of the machine, as shown at the left in Fig. 1, but partly in section as on the line 4—4 in Fig. 5.

Fig. 5 is a sectional elevation taken centrally 45 through a portion of the machine, as on the line and as indicated by the arrows 5—5 in Fig. 4.

Fig. 6 is a sectional detail elevation on the line 6—6 in Fig. 5.

Fig. 7 is an enlarged detail section taken centrally through a portion of the machine, as on the line and as indicated by the arrows 7—7 in Fig. 4.

Fig. 8 is a sectional detail elevation on the line 8—8 of Fig. 7.

Fig. 9 is a sectional elevation similar to Fig. 8,

but showing the feed mechanism adjusted to accommodate a different type of grid plate.

Referring to the drawings more particularly and by reference characters, 10 and 11 designate heavy cast side walls of a main frame, 5 which walls are rigidly connected by suitable cross beams and certain of the superstructure elements. Secured in and to the main frame 10—11 is a motor 12 for supplying power to the machine. The shaft 13 of this motor has a 10 sprocket pinion 14 connected by chain 15 to sprocket gear 16 on one end of a shaft 17 which is journaled in and extends transversely through the main frame. At the opposite side of the machine the shaft 17 has a sprocket pinion 18 operating through sprocket chain 19 and sprocket gear 20 to drive a transverse shaft 21 on which gear 20 is secured. Shaft 21 is also journaled to the main frame structure and has a sprocket gear 22, somewhat smaller than 20, which operates through sprocket chain 23 and pinion 24 to drive an upper shaft 25. The shaft 25 and an intermediate shaft 26 are journaled in bearing extensions of the paste receptacle, designated generally by numeral 27, and have power connection through spur gears 28 and 29. The shaft 26 also has a sprocket pinion 30 which operates through chain 31 and pinion 32 to drive a shaft 33, (Fig. 2) and has another pinion operating through chain 34 and pinion 35 to drive a shaft 36. All the working parts thus far described as well as those subsequently to be set forth rotate or travel in the direction of the indicating arrows.

The shaft 33 has a paste feed roller 37 within the paste chamber 27, which cooperates with an endless paste feed belt 38 (Fig. 5), the forward portion of which extends over two rollers 39 and 40 while the rear end passes about a drum or large roll on the shaft 21, thus receiving conveying power therefrom and transmitting it to the shaft 41 of roller 40, all as set forth in greater detail in my prior application. The shaft 41 now becomes for certain purposes a driving shaft, as will presently be set forth.

Referring to the paste receptacle (27) features, it will be noted that the shafts 33 and 36 are vertically movable, in slots in the receptacle side walls, and that these shafts are journaled at their opposite ends in irregularly shaped levers 42 which fulcrum at their rear ends on shaft 26, and at their front upper ends have a connecting cross bar 43 which extends through slots 44, in the receptacle walls, and passes through a plate 45 forming the front wall of the receptacle. This 50

plate or front wall 45 is consequently mounted for slight vertical movement with respect to the side walls and in conjunction with the paste feed roller 37. The purpose of this construction is to provide means to stop the machine should the normal paste feed be interfered with. Thus should a bolt, nut, or other hard object get into the paste receptacle it will, upon entering the thin discharge space between the roller 37 and the apron 38 (immediately over roller 39), lift the roller 37 above its normal feeding position and thereby will also lift the members 42, 43, and 45; and when this occurs a rod 46 will operate a circuit breaker 47 to stop the motor 12 and thereby stop the machine until the obstruction has been removed. A spring 48a tends to return and maintain the paste feed roll 37 in its normal operative position.

The paste feed mechanisms thus described are substantially similar to those of my aforesaid application Ser. No. 726,744. An important improvement has been made, however, and it relates to the means for dividing the paste layer centrally into two lateral ribbons as it passes between rollers 37 and 39 and is conveyed down with the belt 38 to the grid filling zone between roller 40 and its cooperating roller 48 mounted on shaft 49. It will be noted, with particular reference to Figs. 8 and 9, that the grids to be filled are cast in pairs and that each two grids 50—51 are integrally connected by a medial web or strip 52, which, however, is cut or punched away after the filling operation has been completed and before the grids are placed in batteries. It is of course only necessary to fill the paste into the interstices between the "wires" and "ribs" bounded by the rectangular border or frame of each grid unit, and any paste not so inserted but otherwise adhering to the plate is wasted and frequently becomes objectionable in the treatment and subsequent manipulation of the plate. Hence it is important to prevent the feed or application of paste to the connecting webs 52 as the plates pass into the pasting zone intermediate rollers 40 and 48. To this end the paste feed roller 37, in receptacle 27, may be provided with a central annular rib (as in application Ser. No. 726,744) to remove the central paste strip. This is not always satisfactory, however, because when the roller 37 is vertically adjusted, under action of a control nut 53 on bar 46, to regulate the thickness of the paste layer, the annular rib will raise with it and consequently will be spaced from the feed belt 38 and will not displace or entirely remove the central paste strip. To overcome this objection I have in the present instance provided a central paste strip remover in the form of a narrow shoe 54 (Figs. 4 and 5) formed at the lower end of a bar 55; and this shoe and bar in preference to being attached to and vertically adjustable with plate 45 and roller 37, extends up between the plate 45 and a rigid cross beam 56 for adjustable attachment by a bolt 57 to a bracket 58 rigidly secured to the paste receptacle 27. Thus the shoe 54 will retain its fixed adjusted position with respect to the paste bearing surface of the belt 38 regardless of vertical adjustments effected manually through nut 53 or automatically by an obstructing object wedged under the roller 37. The shoe 54 fits in a slot 59 in a plate 60 which is secured to the lower end of wall plate 45 and has for its purpose to scrape the surplus paste from the underside of the roller 37. This plate 60, being attached to the plate

45, is adjusted vertically with it and with the roller 37. Hence when paste layer thickness adjustments are made, by turning nut 53, the plate 60 will follow with the roller 37 so that independent adjustment will be unnecessary. It may here be noted that the bar 55 is preferably clamped to bracket 58 in such a manner that its lower end is sprung slightly forwardly (to the left in Fig. 5), thus causing the shoe 54 to press against the plate 60, the object being to thereby maintain the shoe more rigidly in operative position.

The shaft 49 of roller 48 is journaled at its ends in adjustable bearing brackets 61, carried by a cross bar 62 and are also yieldable under the action of springs 63 so that roller 48 will be yieldably maintained in operative position with respect to roller 40. Shaft 49 is driven from shaft 41 through spur gears 64 and 65 at one side of the machine (Fig. 1). Gear 64 also operates through an idler 66 and pinions 67 and 68 to rotate a pair of primary grid plate feed rollers 69 and 70; and operates through an idler 71 and pinions 72 and 73 to rotate secondary grid plate feed rollers 74 and 75. Wherever possible the rollers 69, 70, and 75 have their shaft ends mounted in yieldable bearings such as 76 so that the rollers will always be urged and maintained in operative positions under spring pressure. The roller 69 is provided at its end, opposite from pinion 67, with a pinion 77 which meshes with a large spur gear 78 (see Figs. 2, 3, and 4) to drive the grid feed mechanism subsequently to be detailed.

Attention is now redirected to the grid plate advancing and pasting mechanism particularly as shown in Fig. 5, wherein it will be seen that the pairs of rollers 69 and 70, 40 and 48, and 74 and 75 all cooperate to form a central vertical passageway for the grid plates, and all rotate under power and at uniform rates of periphery speed to advance the plates downwardly through the pasting units. Cooperatively associated with these six rollers I further provide a series of guide bars 78, 80, 81, 82, 83, and 84, arranged in pairs and extending the full length of the adjacent rollers. The bars of each pair have opposed guide faces spaced apart equal distances and cooperate with the rollers to form a substantially continuous vertical guideway for the plates.

The upper edges of the guide bars 78—80 are inwardly beveled to form a tapering throat 85 for the edgewise reception of the grid plates 50—51 which are fed successively and vertically thereto by a pair of conveyor discs 86 mounted on a shaft 87. The discs also operate to initially urge the plates down into engagement with the rollers 69—70 as will presently be described. It is here sufficient to note that the grid plates having been received in the throat 85 and passed down between guide bars 78—80 to the rollers 69—70, are gripped by the latter and positively but at uniform speed, progressed down between the guide bars 81—82 to the paste applying zone. As the plates reach the horizontal plane of rollers 40 and 48 they pass into the guide space between bars 83 and 84, the upper end edges of which are arcuately beveled, as shown. Before engaging these bars, however, the plates are filled with the two ribbons of paste which travel down over the incline 38a of the belt 38, and such paste, being of a semi-plastic consistency, immediately fills the grid plate interstices. In fact the paste has a tendency to pass through beyond the surface limit of the grid but this tendency is offset by the counter-action of roller 48 which acts to compress the

paste in the grid and roll it smooth. If there should be an overfeed of paste the excessive paste will build up until it passes forwardly over the roller 48 and falls down on a plate 88 which may 5 guide it into a suitable receptacle (not shown) between or under the base walls 10—11, but with a proper coordination of grid and paste feeds the surplus paste thus discharged is of course reduced to a minimum.

10 It is important to note that the upper edges of the bars 83—84, unlike the disclosure in my former application, are very thin and terminate at the plane level between rollers 40 and 48. This not only permits the bars to more effectively re- 15 move residue paste from roller 48 and apron 38, but also protects the filled grids against the tendency of the roller and apron to pull the paste out of the plates as they pass the median line or common plane between the centers 41 and 49.

20 This has been found in practice to constitute a distinct advantage over my earlier machine arrangement pertaining to this feature.

As the filled grids pass downwardly through the guide bars 83—84 they are engaged by the rollers 25 74—75 and lowered to a pair of conveyor chains 89 which engage the lug extensions 90 and carry the grids away for further treatment and use. To prevent the grids from dropping with a jar onto the chains 89 I provide a pair of yieldable 30 retarder devices 91, described in detail in my copending application Ser. No. 726,744.

It is occasionally necessary to entirely open the grid plate passageway from throat 85 to retarder 91, for purpose of cleaning, repairs, replacements, etc., and it is also desirable to provide means for adjusting the size of the passageway to accommodate different sizes or thicknesses of grid plates. For these reasons the guide bars 80, 82, and 84 are rigidly secured to and the rollers 70, 40 48, and 85 are journaled in the side walls of a carriage unit 92 which is mounted for reciprocating movement longitudinally of the main frame. To adjustably mount the unit 92 I provide it with laterally projecting flanges 93 which are slideable 45 in channels formed by recesses in the upper ends of the base walls 10—11, and cover plates 94 secured to the base walls by bolts 95. The channels for the flanges 93 are preferably restricted vertically so that when the bolts 95 of the cover strip 50 94 are securely screwed down they will clamp the flanges 93 in the side wall recesses, and thus retain and rigidly secure the carriage unit 92 in adjusted positions.

At its forward end the carriage unit 92 is provided with lugs 96 in which are adjustably secured set screws 97, the purpose of which is to contact with the front end edges of the walls 10—11, to thereby adjustably limit the forward motion or movement of the carriage 92 with respect to the 60 main frame of the machine; and it is through this adjustment that the passageway for the grids through the rollers and guide bars, as shown in Fig. 5, is adjusted to accommodate different thicknesses of grid plates. The carriage unit is slideably adjusted when the bolts 95 have been released, by a hand lever 98, which is mounted on a shaft 99 journaled in the main frame structure 10—11, and this shaft at a point intermediate its ends is provided with a crank 100 which is in turn connected by a link 101 to a shaft 102 secured in the carriage unit.

It will now be seen that by loosening the clamping bolts 95 the entire carriage may be shifted back and forth by manipulating the hand lever 75 98, and to the extent permitted by the stop bolts

97 in one direction; and permits ample movement in the forward or opposite direction to permit of cleaning and repairs in the devices which make up the grid plate passageway to and through the pasting zone.

Attention is now directed to the grid plate feed mechanism by which the plates are automatically conveyed into the throat 85 from a supply source, and by which the feed speed of the plates is properly controlled so that there will be no gap between them through the pasting area. This mechanism also provides for the elimination of plates which are oversized, as to thickness, and effectively stops the power application in certain emergencies, whereby no destructive damage will 15 be incurred.

When the carriage 92, which supports the plate feed mechanism, is in its rearward or operative position, the pinion 77 meshes with gear 78 to supply power to the feed mechanism. The gear 20 78 is trunnioned as at 103 (Fig. 4) for rotation on one end of the shaft 87, and this shaft is journaled in bearings 104 on the side walls of the carriage. Secured to the outer side of the gear 78 is an annular steel ring 105, the inner face of which is frictionally engaged by a pair of shoes 106 which are fulcrumed as at 107 to the ends of a cross arm 108 that are fixed on the end of shaft 87. Springs 109 maintain the frictional pressure of the shoes with respect to the gear ring and may be tensioned to regulate the frictional resistance. Thus the gear 78 drives the shaft 87 will slip on the shoes and permit the shaft to slow up or stop when the shaft resistance is sufficient in degree.

Upon its inner side the gear 78 (Fig. 4) has a sprocket pinion 110, rigidly secured as by bolts 111, and this pinion operates a sprocket chain 112 to drive a sprocket gear 113, fixed on a shaft 114 which is journaled to the carriage 92 by adjustable bearings 115. An adjustable pinion 116 (Fig. 2) serves as a tightener or slack adjuster for chain 112.

Immediately adjacent to the inner faces of the carriage (92) sidewalls the positively driven shaft 45 114 is provided with a pair of sprocket gears 117, about which pass sprocket chains 118. The forward ends of these chains pass about sprocket gears 119 on stub shafts 120 in the carriage side walls. The upper runs of the chains 118 travel 50 in longitudinal channels 121 formed in strips 122 secured to the carriage walls, but it should be noted, with particular reference to Figs. 3, 5, 7, 8, and 9, that the chains project slightly above the channels so that they can engage the plate lugs 55 90 and carry the plates suspended by the lugs and without contact with the strips.

At their rear ends the strips support a shelf 123 upon which a stack of grid plates may be placed before being inserted in the feed mechanism by the operator. When the machine is in operation the operator successively inserts groups of plates between the chains 118 and in transverse vertical position so that the lugs 90 will rest upon the chains. As the chains then travel 60 rearwardly the plates are carried through the selector device and up to a position where their upper ends will have peripheral contact with the discs 86, while their lower ends conveniently stop against an angle iron stop 124 adjustably secured 70 to (Fig. 7) as at 125 to a partition member 126 of the carriage frame.

The selector device comprises a shaft 127 having a pair of enlarged hubs 128, transversely spaced, and provided with peripherally spaced 75

notches 129, of sufficient depth to successively engage under the edge of one plate at a time, and thereby lift and carry over the plates, as clearly illustrated in Fig. 7. The shaft is mounted in vertically adjustable bearings 130 and 131 so that it may be secured in two or more positions when different types of plates are to be treated. Thus the shaft is placed in a relative low position, as indicated in Figs. 1, 2, 3, 5, 7, and 8, when plates are being conveyed which have the grid lugs 90 projecting from upper corners of the grids; but when the lugs, such as 90a in Fig. 9, are disposed below the upper corners so that the plates travel at a higher level, then it is necessary to correspondingly raise shaft 127 so that it will have proper engagement with the bottom plate edges. One end of the shaft 127 has a sprocket gear 132, driven by chain 133 from a sprocket gear 134 fixed on end of shaft 81. Thus the speed of shaft 127 is synchronized with that of shaft 81, and when the discs 86 are retarded or stopped, as previously noted, then the shaft 127 will accordingly be retarded or stopped, so that at no time will the plate feed speed of the shaft 127 exceed the conveying speed of the discs. To compensate for vertical adjustments of the shaft 127 I provide a slack and effective length adjuster for the chain 133 in the form of an idler pinion 135 carried by an adjustable bracket 136 (see Fig. 3).

Directly above the shaft 127 the strips 122 are provided with stop lugs 137 against which the lugs 90 of the grid plates stop at approximately the same instant as the lower edge of the grid plate comes into contact with the notches 129 of the shaft hubs 128; and the grids will accumulate against the stop lug 137, as indicated in Fig. 7, until the shaft 127 successively raises the grid plates, at which time they are carried over the stop lugs 137 and again carried toward the discs 86. Forwardly of the stop lugs 137 and at a slightly higher elevation, are a pair of latches 138 which are adjustably secured as by bolts 139 to arms 140 of a lever 141 with which the two arms 140 are integral. This lever 141 extends across the carriage unit 92, as shown in Figs. 4, 8, and 9, and is pivotally secured thereto for tilting movement as at 142. The latches 138 are normally held down in operative position under the action of gravity, supplemented by a spring 143. The lever 141 has an arm 144 which is operative when depressed or moved downwardly to press a button 145 of a switch box 146 to break the circuit to the motor 12 and thus stop the machine.

It will be noted with particular reference to Figs. 4, 5, and 7 that the latch 138 is adjusted to such a position that there will be a gap 147 between its rear end and the forward edge or face of the lug 137; and this gap is of such a size (longitudinally of the machine) that it will permit a grid plate of normal thickness to pass upwardly over the stop lug 137 and immediately behind the latch 138 so that it will not engage or lift the latch 138. If the thickness of the grid plate, however, is greater than the normal thickness of grids intended to be pasted, then such plate will engage under one or both of the latches 138 and thereby tilt the lever 141 sufficiently so that the arm 144 will press the button 145 of the switch box 146 and thereby stop the machine until the oversized grid plate has been removed and normal operation restored.

At 148 in Fig. 7 I have indicated a grid plate 75 which is thicker than the other plates, and

which will be operative upon reaching the stop lug 137 and upon being elevated by the shaft 127 to engage the latch 138 and break off the current supply to the motor. It will be noted that the arm 144 of the lever 141 has a yieldable presser pin 149 for contact with the switch button 145 so that the lever may tilt further forwardly than is necessary to merely actuate the switch button, if such action becomes necessary. It will of course be obvious that by adjusting the latch members 138 forwardly or rearwardly with respect to the lever arms 140, the machine may readily be adjusted to accommodate any particular type of grid plate, and will give absolute assurance that no grid plate of more than the desired thickness will pass into the pasting mechanism.

As previously noted, the shafts 87 and 127 are synchronously driven, with a result that their feeding or conveying capacities will always be the same. To insure proper pickup operation by the discs 86, however, it is desirable that an ample supply of grid plates be always maintained in peripheral engagement with the discs, and consequently a supply of approximately a dozen plates are preferably provided immediately adjacent the discs, as indicated in Fig. 7.

Another purpose for the stop lugs 137 is to prevent an over-accumulation of plates adjacent the pickup discs 86, which would have the tendency to unduly retard the disc movement. It will be remembered that the discs 86 are frictionally driven through the shoes 106, and this for the specific purpose of permitting the discs to be slowed up or if necessary stopped when clogging or other resistance so requires; and as the grid plates are always supported by their lugs 90 on the chains 118, they must permit the chain to slide under the lugs when the plates are held stationary. And this of course increases the frictional resistance of the grid plates on the disc peripheries to a point where such resistance might easily stop the plates should there be a sufficient accumulation of grid plates immediately in front of the discs.

At regularly spaced intervals about their peripheries the discs 86 are provided with notches 150 which are each of a length slightly greater than the vertical dimension of the grid plate lug 90, so that the lug may pass entirely into the notch under the action of the conveyor chains 118, and when one pair of notches 150 is in proper position to receive the opposite lugs 90 of the grid plate immediately adjacent the discs. The plates 86 are disposed immediately adjacent to the chains 118, and the notches 150 are of such a form that they will engage under the lower edges of the plate lugs and lift them up and over the shaft 87, while permitting the grid plates to retain their vertical positions until dropped into the throat 85. After the grid plates successively pass over the center of the shaft 87, however, they drop down into the other and slightly larger ends of the notches 150 so as to be less liable to disengage therefrom until the proper disengaging position has been reached. It will be noted that as each plate approaches its final vertical position over the throat 85, as indicated by the dotted lines at the left in Fig. 7, its upper edge portion will engage the lower end of a guide plate 151 in such a manner as to tilt the lower end of the plate rearwardly and insure its proper entry into the throat 85. Without some such means it has been found that the plates will occasionally swing over in front of the guide 75

bar 80 and thus interrupt the proper operation of the machine.

The guide plate 151 is attached to a bar 152 which is secured in a pair of bracket extensions 153 of the transverse beam 56. The outer ends of the bar 152 oscillatably support a pair of depending arms 154 which engage against the rear edges of the discs 86 for the purpose of holding the grid plate lugs in the recesses 150 of the discs 86 until they are ready to be discharged therefrom. The arms 154 have rearward extensions 155 connected to springs 156, with a result that the arms 154 are yieldably retained in contact with the plate carrying discs.

From the foregoing it will be seen that the grid plates will be positively engaged in the disc notches 150 until the notches reach the lowermost extremities of the arms 154, at which time the grid plates proper will be in a position well down in the passageway between the guide bars 79 and 80. As the discs then continue to rotate the notches 150 will discharge the grid plate lugs, but in order to prevent any possible sticking of the lugs in the notches I have provided the rear end of the carriage 92 with a pair of fixed cams 157 which will engage the forward faces of the plate lugs, and discharge them from the disc notches. It may here be noted that the normal plate feeding speed of the feed rolls 69 and 70 is somewhat slower than the plate feeding speed of the discs 86, with a result that when a plate is conveyed into the throat 85 by the discs 86 the lower edge of said plate will contact with the upper edge of the preceding plate, which is then in conveying engagement with the rollers 69 and 70. Consequently the plate passing into the throat 85 cannot move downwardly as fast as the discs 86 would normally be driven by the shaft 87; but inasmuch as the notches 150 are sufficiently deep to entirely receive the plate lugs, the shoulders 150a at the upper ends of the downwardly moving notches will engage the lugs and press the engaged plate into firm contact with the upper edge of the preceding plate. And as the speed of the plates passing down through the rollers 69 and 70 is less than the normal feed speed of the shaft 87, the shoes 106 will slip in the ring 105 sufficiently to permit the disc movement to be slowed up, and as the disc movement is slowed up the feeding speed of the shaft 127 is also retarded. Under these circumstances the plates moving down into the pasting zone will be traveling at a uniform rate of speed, and as the plates delivered from the discs are always being crowded against the plates in the passageway there will be no interruption in the continuity of feed, and there will be no gaps or spaces between any two adjacent grid plates.

As the grid plates pass downwardly through the pasting area they are, as previously mentioned, discharged between rollers 74 and 75 and through the friction devices 91 so that they will drop between the conveyor chains 89, upon which chains the opposite projecting lugs 90 of the plates will rest in the same manner as they were previously carried on the chains 118. The two transversely spaced conveyor chains 89 are supported at their forward ends on sprocket gears 158 of shaft 159 journaled in the base of the machine; and the rear ends of the chains pass over sprockets 160 secured to stub shafts 161 journaled in frame extensions 162 of the frame castings 10 and 11. Adjustable idler pinions 163 are arranged to take up or adjust the slack in the conveyor chains 89. The shaft 159 has a sprock-

et 164 driven by a sprocket chain 165 from a sprocket pinion 166, which is in turn driven from shaft 17 through spur gears 167.

One of the stub shafts 161 has a small spur pinion 168 which meshes with and drives a second but larger pinion 169. This second pinion meshes with and drives a spur gear 170 on a shaft 171 also journaled in the frame extensions 162. The shaft 171 is provided within the extensions 162 and immediately adjacent to the conveyor chains 39 with a pair of discs 172, which rotate with the shaft 171 and serve to engage under the lugs of the grid plates and transfer them from the conveyor 89 to a second pair of conveyor chains 173 which are disposed in substantial alignment with the chains 89, but slightly spaced beyond the rear ends thereof.

The chains 173 operate over sprocket gears 174 which are mounted on stub shafts 175 in a conveyor frame 176 suitably supported either by the extensions 162 or by a second frame work such as indicated at 177. The conveyor 173 has for its purpose to convey the grid plates away from the pasting machine, and may be used to convey the pasted grids directly into a drying oven or other place for further treatment. It may be noted that the transferring discs 172 are employed with particular advantage in this conveyor combination inasmuch as it will convey the plates from the conveyor 89 to the conveyor 173 while maintaining a uniform spacing between the grids, and regardless of the relative speeds of the two conveyor systems.

Thus if the conveyor 89 travels at a relatively faster speed the plates discharged from the pasting area will be spaced a considerable distance apart, possibly from eight to ten inches. The conveyor 173, on the other hand, may travel at a very slow rate of speed, but the plates will be transferred to it at a uniform rate, and consequently they will be much more closely associated or grouped on the conveyor 173, but still will have a uniform spacing, and such spacing may not be more than a half an inch to one inch, if such spacing is desired for instance in the drying ovens.

While the operation of the machine will no doubt be clearly understood from the foregoing specification, it may be briefly reviewed as follows:

When the machine is to be put in operation the receptacle 27 is first supplied with a quantity of the paste material, and a supply of grid plates is in readiness on the shelf 123. The motor 12 is now started by closing a starter switch, preferably located in the switch box 146, and such switch may be closed by pressing a starter button 178. With the motor running, power is conveyed through the motor shaft 13, sprocket pinion 14, sprocket chain 15, gear 16, shaft 17, pinion 18, chain 19, and gear 20, to the shaft 21 which carries the rear end of the belt 38 and thereby moves the belt in the direction indicated by the arrows in Fig. 5.

The shaft 21 then supplies power to the paste feed roll 37 through gear 22, chain 23, gear 24, shaft 25, gear 28, gear 29, shaft 26, gear 30, chain 31, and gear 32 on the shaft 33 of the said feed roll. The roller 37 and apron 38 now cooperate to compress a layer of paste on the belt, and such paste layer then moves down over the incline 38a to the paste applying area between the rollers 40 and 48. Meanwhile the shoe 54 is in contact with the belt 38 to remove a central strip of paste in order that active material may not be applied to the connecting web 52 between the 75

grid units. The thickness of the paste layers thus conveyed to and forced into the grid interstices may be regulated by turning the nut 53 which controls the vertical position of the roller 37 and the adjusting plate 60. Should any hard object get into the paste material in the receptacle 27 it will, upon coming into engagement under the roller 37, wedge the latter upwardly and thereby operate through members 45, 43, 46, 10 and 53, to release the circuit opener 47 and thereby shut off the current supply to the motor until the object has been removed. Thus such an obstruction will stop the operation of the machine in time to prevent any destructive damage.

15 The so called secondary grid plate feeding mechanism which conveys the grid plates downwardly from the receiving throat 85 through the pasting area, and to the conveyor chains 89, is driven from the roller 40 at the forward end of 20 the apron 38, as shown in Fig. 5. The shaft 41 of this roller 40 is provided at one side of the machine, as shown particularly in Fig. 1, with a spur gear 64 which meshes with and drives two idler pinions 66 and 71, and also meshes with 25 and drives a gear 65 on the shaft 49 of roller 48, this shaft being journaled in adjustable bearing members 61 on the carriage 92. As the gears 64 and 65 are of similar diameters, the rollers 40 and 48 will be driven at similar speeds, and 30 to secure the best results these two rollers should have their axes disposed in a common horizontal plane. The idler pinion 66 drives the rollers 69 and 70 through intermeshing pinions 67 and 68, and the idler pinion 71 drives the lowermost feed 35 rollers 74 and 75 through intermeshing pinions 72 and 73. Thus all of the rollers 69—70, 40 and 48, and 74—75 all successively function to grip the downwardly moving grid plates and convey them at a predetermined and constant rate 40 of speed through the feeding area and in proper synchronized relationship to the feeding speed of the paste apron 38.

Supplementing these grid conveying rollers are provided a series of guide bars 79, 80, 81, 82, 83, 45 and 84 arranged in pairs and spaced in such a manner as to form a vertical passageway in conjunction with the rollers so that the plates will be properly guided and conveyed while traveling through such passage.

50 The primary grid plate conveying mechanism has both positively and frictionally driven parts to the end that the grid plates may be initially conveyed in the most efficient and practical manner to the receiving throat 85 of the secondary conveyor mechanism. To this end the roller 69 of the secondary conveyor mechanism operates through the pinion 71 to drive the gear 78 which is rotatable on the shaft 87. This gear operates through the sprocket pinion 110 and chain 112 55 to drive the large gear 113 on shaft 114 to positively actuate the conveyor chains 118 which initially receive the grid plates. The gear 78 then functions through the friction shoes 106 to frictionally or yieldably transmit power to the 60 shaft 87 and discs 86, and thereby through the pinion 134, chain 133, and pinion 132 to operate the selector shaft 127.

As the grid plates now move rearwardly on the conveyor chains 118 they stop against the lugs 70 137 while their lower ends are brought into engagement with the notches 129 of the hubs 128. The shaft 127 now successively lifts the grid plates, permitting them to pass over the lugs 137 and into peripheral contact with the discs 86. Should an oversized plate get into the group,

however, it will not pass up through the gap 147, but will engage the latch 138 and thereby tilt the lever 141 until the circuit breaker 145 is actuated by the pin 149 of the lever arm 144, thus shutting off power to the machine. When the objectionable oversized grid has then been manually removed, the operation may be continued by pressing the starter switch button 178.

As the grid plates are brought into contact with the discs 86 their lugs will successively pass 10 into the notches 150, which will then lift the grids from the conveyor 118 and carry them over to a position where they will be guided into the throat 85 of the secondary feeding mechanism. To assist in properly conveying and guiding the 15 plates the guide plate 151 acts upon the upper edge portions of the grid plates and swings their lower ends into the throat 85. As the grid feeding speed of the grids 86 is somewhat greater than the normal conveying speed of the secondary 20 conveyor rolls, the lower edge of the grid passing into the space between guide bars 79 and 80 will contact with the upper edge of the preceding plate; and when this occurs there will be a reaction through the upper plate causing the 25 latter to engage against the shoulders 150a of the disc notches, and thereby resist the normal movement of the discs. This resistance is carried back to the shoes 106 which will then slip 30 within the ring 105, permitting the required 35 interruption or slowing down of the disc movement. While this resistance reaction is being transmitted it is necessary that the grid plate lugs be retained in proper position in the notches 150, and to this end I have provided the yieldably movable arms 154 which act against the 40 rear edges of the discs, and thereby insure proper retention of the lugs in the disc notches. When, however, the grid plate being conveyed is sufficiently far down in the passageway of the 45 secondary feeding mechanism so that it will be firmly gripped and held by the conveyor rolls 69 and 70, then the grid plate lugs will be positively disengaged from the disc notches 150 through the action of the stationary lugs 151 carried at the rear end of the carriage 92.

As the grid plates move down into the paste feeding area immediately above and between the 50 rollers 40 and 48, and below the guide bars 81 and 82, the paste is forced into the grid openings and is firmly pressed in place through the action of the roller 48 and the portion of the apron 38 which travels over the roller 40, and as the filling is thus completed the plates travel down through the guide bars 83 and 84 for 55 delivery to the conveyor 89. Inasmuch as the upper edges of the guide bars 83 and 84 are arcuately recessed and tapered so as to project to the same elevation as the shaft centers 41 and 49, they will receive the grids at exactly 60 the proper instant so that the succeeding surface movement of the roller 48 and belt 38 will not have a tendency to withdraw the paste from the plates. Being formed in this manner the bars 83 and 84 also serve to effectively shave or 65 scrape the belt 38 and roller 48 so that they will be clean as they pass downwardly from the pasting area.

As the plates are delivered to the conveyor 70 89 they travel rearwardly to the frame extension 162, the conveyor being driven from shaft 17 through the spur gears 167, the sprocket gear 166, chain 165, and the sprocket 164 on shaft 159. As the grids leave the end of the conveyor chain 89 the plate lugs immediately engage the pe- 75

ripheral edges of the discs 172 which then carry them over and deposit them upon the conveyor 173.

It is understood that suitable modifications 5 may be made in the structure as disclosed, provided such modifications come within the spirit and scope of the appended claims. Having now therefore fully illustrated and described my invention, what I claim to be new and desire to 10 protect by Letters Patent is:

1. In a grid plate pasting machine having a passageway for the movement of the plates therethrough, means for applying paste to the plates while progressing through the passageway, 15 a horizontal plate conveyor, and a rotatable carrier for removing the plates from the conveyor and feeding them into the passageway.

2. In a grid plate pasting machine having a passageway for the movement of the plates there- 20 through, means for applying paste to the plates while progressing through the passageway, a horizontal plate conveyor, and a rotatable carrier disposed between the conveyor and passageway for lifting the plates from the conveyor, 25 carrying them up over the axis of the carrier and depositing them edgewise into the passageway.

3. In a grid plate pasting machine having a passageway for the movement of the plates there- 30 through, means for applying paste to the plates while progressing through the passageway, a conveyor for conveying plates toward the passageway in vertical positions, a rotatable carrier for removing the plates from the conveyor and carrying 35 them while still in vertical position to a delivery position into the passageway.

4. In a grid plate pasting machine having a passageway for the movement of the plates there- 40 through, means for applying paste to the plates while progressing through the passageway, a conveyor for conveying plates toward the passageway in vertical positions, a rotatable carrier for removing the plates from the conveyor and carrying 45 them while still in vertical position to a delivery position into the passageway, said rotatable carrier having peripherally spaced means for successively engaging plates advanced by the conveyor.

5. In a grid plate pasting machine having a passageway for the movement of the plates there- 50 through, means for applying paste to the plates while progressing through the passageway, a conveyor for conveying plates toward the passageway in vertical positions, a rotatable carrier for 55 removing the plates from the conveyor and carrying them while still in vertical position to a delivery position into the passageway, said rotatable carrier having peripherally spaced means for successively engaging plates advanced by the conveyor, and said conveyor being operative to yieldably urge the plates thereon into contact with the carrier.

6. In a grid plate pasting machine having a passageway for the movement of the plates there- 65 through, means for applying paste to the plates while progressing through the passageway, a rotatable carrier for successively conveying plates to the passageway from a position spaced from the plane thereof and for urging them therewith, 70 and means for yieldably rotating the carrier whereby resistance to plates entering the passageway will retard the carrier movement.

7. In a grid plate pasting machine having a passageway for the movement of the plates there- 75 through, means for applying paste to the plates

while progressing through the passageway, a rotatable carrier having peripherally spaced notches for engagement by the plates and for successively advancing plates to the passageway, and a cam acting means for positively disengaging the plates from the notches after the plates have moved a predetermined distance into the passageway.

8. In a grid plate pasting machine having a passageway for the movement of the plates there- 10 through, means for applying paste to the plates while progressing through the passageway, a rotatable carrier having peripherally spaced notches for engagement by the plates and for successively advancing plates to the passageway, and 15 means coacting with the carrier to insure retention of the plates in the notches until the plates have advanced to a predetermined delivery position with respect to the passageway.

9. In a grid plate treating machine having a vertical passageway for the movement there- 20 through of grid plates having lateral extensions, a conveyor engageable with said extensions to convey the plates in vertical positions toward the passageway, a carrier for transferring the plates from the conveyor and delivering them edgewise into the passageway, said carrier comprising a 25 pair of rotary members having spaced notches for engaging said lateral plate extensions and supporting the plates thereby.

10. In a grid plate treating machine having a vertical passageway for the movement there- 30 through of grid plates having lateral extensions, a conveyor engageable with said extensions to convey the plates in vertical positions toward the 35 passageway, a carrier for transferring the plates from the conveyor and delivering them edgewise into the passageway, said carrier comprising a pair of rotary members having spaced notches for engaging said lateral plate extensions and 40 supporting the plates thereby, said extensions serving as supporting pivots to permit the plates to hang in vertical positions as they pass over the carrier axis and to discharge positions with respect to the passageway.

11. In a grid plate treating machine, a plate passageway having an upwardly flared plate receiving opening, a carrier disposed adjacent the throat and for rotation on a horizontal axis, means at the periphery of the carrier for laterally 50 suspending the plates and permitting them to swing and retain substantially vertical positions while being carried over said axis, and means for engaging the plates as they approach a position over the opening to guide them edgewise there- 55 into.

12. In a grid plate pasting machine, a pair of parallel cooperating rollers between which the plates pass and by which the paste is pressed into the plate from opposite sides, means for applying paste to the plates before they pass through the rollers, and a pair of spaced guide plates for receiving the plates acted upon by the rollers, said guide plates having tapered edges terminating substantially at the plane through 60 the axes of the two rollers.

13. In a grid plate pasting machine, a pair of parallel cooperating rollers between which the plates pass and by which the paste is pressed into the plate from opposite sides, means for applying paste to the plates before they pass through the rollers, and a pair of spaced guide plates for receiving the plates acted upon by the rollers, said guide plates having tapered edges terminating substantially at the plane through the axes of 70 75

the two rollers, said paste applying means comprising an endless belt passing about one of the rollers.

14. In a machine for pasting grid plates having two laterally arranged grids to a plate, the combination comprising means forming a passageway for a row of plates, means for forming a continuous ribbon of paste for application to the grids in the passageway, and means separating said ribbon centrally into two strips one for the grids at each side of the row.

15. In a machine for pasting grid plates having two laterally arranged grids to a plate, the combination comprising means forming a passageway for a row of plates, means for forming a continuous ribbon of paste for application to the grids in the passageway, and means for removing a longitudinal strip of paste from the ribbon before the paste is applied to the row of plates.

16. In a grid plate pasting machine having a passageway for the movement for the plates therethrough, means for applying paste to the plates in the passageway, a conveyor for conveying plates toward the passageway, and a transferring device movable upwardly adjacent the delivery end of the conveyor to successively remove the plates therefrom, and movable downwardly adjacent the passageway to discharge the transferred plates thereinto.

17. In a grid plate pasting machine having a passageway for the movement of the plates therethrough, means for applying paste to the plates in the passageway, a conveyor for conveying 35 plates toward the passageway, and a transferring device movable upwardly adjacent the delivery end of the conveyor to successively remove the plates therefrom, and movable downwardly adjacent the passageway to discharge the transferred plates therewith, said transferring device 40 having means engageable with upper parts of the plates and permitting tilting of the latter whereby the plates will be transferred in substantially vertical positions.

45 18. In a grid plate pasting machine having a passageway for the movement of the plates therethrough, means for applying paste to the plates in the passageway, an endless conveyor having a run movable toward the passageway
50 and for supporting grid plates thereon, a transferring device having a portion movable upwardly adjacent the conveyor to remove plates therefrom and deliver them to the passageway, said device having frictional engagement with
55 and serving as a stop for an accumulation of grid plates on the conveyor while permitting the conveyor to continue its movement.

19. In a grid plate pasting machine having a passageway for the movement of the plates therethrough, means for applying paste to the plates in the passageway, an endless conveyor having a run movable toward the passageway and for supporting grid plates thereon, a transferring device having a portion movable upward-
60 ly adjacent the conveyor to remove plates therefrom and deliver them to the passageway, said device having frictional engagement with and serving as a stop for an accumulation of grid plates on the conveyor while permitting the con-
65 veyor to continue its movement, and means for limiting the number of accumulated grid plates on the conveyor to thereby restrict the frictional resistance of such accumulated grid plates on the transferring device.

75 20. In a grid plate pasting machine having a

passageway for the movement of the plates therethrough, means for applying paste to the plates in the passageway, an endless conveyor having a run movable toward the passageway and for supporting grid plates thereon, a transferring device having a portion movable upwardly adjacent the conveyor to remove plates therefrom and deliver them to the passageway, said device having frictional engagement with and serving as a stop for an accumulation of grid plates on the conveyor while permitting the conveyor to continue its movement, and means for limiting the number of accumulated grid plates on the conveyor to thereby restrict the frictional resistance of such accumulated grid plates on the transferring device, said limiting means comprising a member disposed in advance of the transferring device for restricting the grid plate movement with the conveyor, and a release mechanism associated with said member and operated in synchronism with the transferring device. 5 10 15 20

21. In a grid plate pasting machine having a passageway for the movement of the plates therethrough, means for applying paste to the plates in the passageway, an endless conveyor having a run movable toward the passageway and for supporting grid plates thereon, a transferring device having a portion movable upwardly adjacent the conveyor to remove plates therefrom and deliver them to the passageway, said device having frictional engagement with and serving as a stop for an accumulation of grid plates on the conveyor while permitting the conveyor to continue its movement, said conveyor comprising parallel chains laterally engageable with the plates in a manner permitting the plates to be carried in suspended positions therebetween, and said transferring device comprising a pair of side members associated with and adjacent to the respective chains. 25 30 35 40

22. In a grid plate pasting machine having a passageway for the movement of the plates therethrough, means for applying paste to the plates in the passageway, a conveyor for conveying plates toward the passageway, a transferring device for transferring plates from the conveyor to the passageway, a stop member associated with the conveyor to restrict the movement therewith of grid plates carried thereby, and a release mechanism for intermittently releasing grid plates with respect to such stop whereby such released plates may continue under the conveyor action toward the transferring device. 45 50

23. In a grid plate pasting machine having a passageway for the movement of the plates therethrough, means for applying paste to the plates in the passageway, a conveyor for conveying plates toward the passageway, a transferring device for transferring plates from the conveyor to the passageway, a stop member associated with the conveyor to restrict the movement therewith of grid plates carried thereby, and a release mechanism for intermittently releasing grid plates with respect to such stop whereby such released plates may continue under the conveyor action toward the transferring device, said release mechanism comprising a rotatable member having peripherally spaced means for successively engaging the plates on the conveyor and lifting them over the stop member. 55 60 65 70

24. In a grid plate pasting machine having a passageway for the movement of the plates therethrough, means for applying paste to the plates in the passageway, means for supporting a supply of grid plates at a point spaced from the 75

receiving end of the passageway, a rotatable carrier disposed between the supporting means and the passageway and operative upon being rotated to successively lift the plates from the said supply, convey them to, and deliver them into the receiving end of the passageway.

25. In a grid plate pasting machine having a passageway for the movement of the plates therethrough, means for applying paste to the plates 10 in the passageway, means for supporting a supply of grid plates at a point spaced from the receiving end of the passageway, a rotatable carrier disposed between the supporting means and the passageway and operative upon being rotated 15 to successively lift the plates from the said supply, convey them to, and deliver them into the receiving end of the passageway, said carrier comprising a pair of transversely spaced wheels having circumferentially spaced, peripheral notches 20 adapted to tiltably receive and support portions of the plates.

26. In a grid plate pasting machine having a passageway for the movement of the plates therethrough, means for applying paste to the plates 25 in the passageway, means for supporting a supply of grid plates at a point spaced from the receiving end of the passageway, a rotatable carrier disposed between the supporting means and the passageway and operative upon being rotated 30 to successively lift the plates from the said supply, convey them to, and deliver them into the receiving end of the passageway, said carrier comprising a pair of transversely spaced wheels having circumferentially spaced, peripheral notches 35 adapted to tiltably receive and support portions of the plates, said wheels being operative to exert edgewise pressure on the plates as they enter the passageway so as to urge the plates thereinto.

27. In a grid plate pasting machine having a passageway for the movement of the plates therethrough, means for applying paste to the plates in the passageway, means for supporting a supply of grid plates at a point spaced from the receiving end of the passageway, a rotatable carrier 40 disposed between the supporting means and the passageway and operative upon being rotated to successively lift the plates from the said supply, convey them to, and deliver them into the receiving end of the passageway, said carrier comprising a pair of transversely spaced wheels having circumferentially spaced, peripheral notches 45 adapted to tiltably receive and support portions of the plates, said wheels being operative to exert edgewise pressure on the plates as they enter the passageway so as to urge the plates thereinto, and yieldable means for rotating the carrier whereby the movement of the wheels may be retarded when the said edgewise pressure on a plate meets with resistance of a preceding plate 50 moving at a slower rate of speed in the passageway.

28. In a grid plate pasting machine having a passageway for the movement of the plates therethrough, means for applying paste to the plates 55 in the passageway, means for supporting a supply of grid plates at a point spaced from the receiving end of the passageway, a rotatable carrier disposed between the supporting means and the passageway and operative upon being rotated 60 to successively lift the plates from the said supply, convey them to, and deliver them into the receiving end of the passageway, said passageway being defined in part by a primary pair of power driven feed rolls adapted to grip the plates 65

discharged by the carrier and advance them further into the passageway.

29. In a grid plate pasting machine having a passageway for the movement of the plates therethrough, means for applying paste to the plates 5 in the passageway, means for supporting a supply of grid plates at a point spaced from the receiving end of the passageway, a rotatable carrier disposed between the supporting means and the passageway and operative upon being rotated 10 to successively lift the plates from the said supply, convey them to, and deliver them into the receiving end of the passageway, said carrier comprising a pair of transversely spaced wheels having circumferentially spaced, peripheral notches 15 adapted to tiltably receive and support portions of the plates, and yieldable means cooperating with the wheels, at the delivery side of the carrier, for retaining the plate engagement in said notches until the carrier has rotatably advanced to a predetermined position. 20

30. In a grid plate pasting machine having a passageway for the movement of the plates therethrough, means for applying paste to the plates 25 in the passageway, means for supporting a supply of grid plates at a point spaced from the receiving end of the passageway, a rotatable carrier disposed between the supporting means and the passageway and operative upon being rotated 30 to successively lift the plates from the said supply, convey them to, and deliver them into the receiving end of the passageway, said carrier comprising a pair of transversely spaced wheels having circumferentially spaced, peripheral notches 35 adapted to tiltably receive and support portions of the plates, and yieldable means cooperating with the wheels, at the delivery side of the carrier, for retaining the plate engagement in said notches until the carrier has rotatably advanced to a predetermined position, said yieldable means comprising a pair of lever arms having portions peripherally engageable with the wheels so as to effectively close the plate engaged notches thereof as they pass such lever arm 40 portions. 45

31. In a grid plate pasting machine having a vertically disposed passageway for the end to end movement therethrough of grid plates having laterally extending lugs, one lug at each side edge of the plate, said passageway including a 50 pair of primary power driven rollers adapted to grip the incoming plates and advance them into the passageway, a carrier for supplying plates successively to the rollers of the passageway, said carrier comprising lateral members having spaced 55 notches adapted to receive said plate lugs to support the plates thereby, and friction driven means for operating the carrier members at a grid plate advancing speed in excess of that of said passageway rollers but permitting the carrier member 60 movement to be retarded by resistance from a plate in engagement with the slower moving rollers, thereby causing the plates to advance through the passageway in edge to edge contact with each other. 65

32. In a grid plate pasting machine, a pair of parallel cooperating rollers between which the plates pass and by which the paste is pressed into the plate from opposite sides, means for applying paste to the plates before they pass 70 through the rollers, and a pair of spaced guide plates for receiving the plates acted upon by the rollers, one of said guide plates having a tapered edge terminating substantially at the plane through the axes of the two rollers. 75

33. In a machine for pasting grid plates having two laterally arranged grids to a plate, the combination comprising means forming a passageway for a row of plates, means for forming a continuous ribbon of paste for application to the grids in the passageway, a carrier for the ribbon, and a shoe associated with the carrier for longitudinally separating the paste ribbon into two strips for application to the grids at respectively 5 opposite sides of the plates.
- 5 34. In a machine for pasting grid plates having

two laterally arranged grids to a plate, the combination comprising means forming a passageway for a row of plates, means for forming a continuous ribbon of paste for application to the grids in the passageway, adjustable means for determining the thickness of the paste ribbon, and means independent of said adjustable means for separating the paste ribbon into two strips one for the grids at each side of the row. 10

ARTHUR D. LUND.
